UNITED STATES PATENT OFFICE.

WILLIAM P. WOERNER, OF LANCASTER, PENNSYLVANIA.

DESIGN FOR A TOY CANE.

Application filed November 19, 1920. Serial No. 425,275. Term of patent 14 years.

To all whom it may concern:

Be it known that I, WILLIAM P. WOERNER, a citizen of the United States of America, residing at Lancaster, in the county of Lancaster and State of Pennsylvania, have invented a new, original, and ornamental Design for a Toy Cane, of which the following is a specification, reference being had to the accompanying drawings, forming a part hereof.

The figure is a perspective view showing my new design for a toy cane.

I claim:

The ornamental design for a toy cane as shown.

WILLIAM P. WOERNER.

Witness:

D. M. OSTERMAN.
